UNITED STATES PATENT OFFICE.

RUDOLPH H. KLAUDER, OF PHILADELPHIA, PENNSYLVANIA.

FASTENING FOR ELECTRICAL CONDUCTORS.

1,001,864.

Specification of Letters Patent. Patented Aug. 29, 1911.

Application filed December 15, 1910. Serial No. 597,545.

To all whom it may concern:

Be it known that I, RUDOLPH H. KLAUDER, a citizen of the United States, residing at Philadelphia, county of Philadelphia, State 5 of Pennsylvania, have invented certain new and useful Improvements in Fastenings for Electrical Conductors, of which the following is a specification.

The principal objects of the present invention are to provide a fastening which shall hold an electric wire or conductor firmly and securely and in such manner that proper electrical contact is insured between the fastening and the wire or conductor; to provide such a fastening which will accommodate wires or conductors of different sizes; and to provide a fastening which shall be of simple construction yet durable and efficient in its engagement with the wire or 20 conductor.

The invention will be claimed at the end hereof but will be first described in connection with the accompanying drawings in which—

25 Figure 1, is a perspective view of a fastening embodying features of the invention showing in connection therewith a wire or conductor. Figs. 2 and 3, are similar views showing the fastening without the wire or conductor and illustrating the parts in different positions, and Fig. 4, is a side view of the fastening embodying features of the invention and adapted for holding wires or conductors of different diameters.

35 In the drawings 1, is a shank consisting of two plates or metal ribbons 3 and 4, superposed upon and in facial contact with each other.

40 2, is an opening for attaching means, such as 5; and it is formed by making a hole in the shank.

The inner end of the plate 3, is shorter than the inner end of the plate 4, and the inner end of the plate 3, is arranged in a single curve to form a wire holding abutment 6. The inner end of the plate 4, is comparatively long and its body part is arranged in the form of a spring loop 7. The end 8, of the plate 4, is curved to form a holding jaw. The holding jaw 8, is normally drawn into contact with the abutment 6, by the spring or resiliency of the loop 7. The working parts of the jaw and abutment which coöperate with each other and hold the wire or contact are co-extensive with the plates so that good electrical con-

tact over an extended surface is insured. By curving the abutment and jaw on generally helical lines, as in Fig. 4, they are adapted to coöperate with wires or conductors of different sizes. The plates 3 and 4, may be separate or they may be made by folding a single plate or ribbon as is shown at 9.

In use the wire or conductor 10, is held 65 between the jaw and abutment in such a way that they have contact therewith throughout their entire surfaces in the direction of their widths and the spring or resiliency of the loop 7, serves to insure good 70 electrical contact. The fastening may be used, if desired, as a terminal or, if properly insulated, as a support. The fact that the plates are arranged in facial contact to form a shank provides for convenience 75 in applying the fastening and also imparts strength to it and insures a relatively firm abutment and an exceedingly resilient or springy jaw.

What I claim is:

1. A fastening for electrical conductors comprising a shank consisting of two plates arranged in facial contact with each other and the inner end of one plate being comparatively short and arranged in a single curve to form a wire holding abutment co-extensive with the face of the plate and the inner end of the other plate being comparatively long and having its body part arranged to form a spring loop and its end curved to form a holding jaw co-extensive 85 with the face of the plate and normally drawn into engagement with the abutment by the spring or resiliency of the loop, substantially as described. 90

2. A fastening for electrical conductors comprising a shank consisting of a metallic ribbon doubled on itself to provide two plates arranged in facial contact with each other and the inner end of one plate being comparatively short and arranged in a single curve to form a wire holding abutment and the inner end of the other plate being comparatively long and having its intermediate part arranged to form a spring loop and its end curved to form a holding jaw, 100 substantially as described. 105

3. A fastening for electrical conductors comprising a shank consisting of two plates arranged in facial contact with each other and perforated to provide an attaching means opening and the inner end of one 110

plate being comparatively short and arranged in a single curve to form an abutment and the inner end of the other plate being comparatively long and having its body part arranged to form a spring loop and its end curved to form a holding jaw, substantially as described.

4. A fastening for electrical conductors comprising a shank consisting of two plates arranged in facial contact with each other and the inner end of one plate being comparatively short and arranged in a helical

curve and the inner end of the other plate being comparatively long and having its body part arranged to form a spring loop ¹⁵ and its end arranged in a helical curve to form a holding jaw, substantially as described.

In testimony whereof I have hereunto signed my name.

RUD. H. KLAUDER.
